United States Patent Office

Des. 225,588
Patented Dec. 19, 1972

225,588

COMBINED BLOTTER PAD AND PORTFOLIO

Rex Clifford Testro, 56 Campbell St., East Kew, Victoria, Australia, and Keith Royal Testro, 22 Kellett Grove, Kew, Victoria, Australia

Filed Dec. 21, 1970, Ser. No. 26,598

Term of patent 14 years

Int. Cl. D3—99

U.S. Cl. D87—3

FIG. 1 is a perspective view of a combined blotter pad and portfolio showing our new design in a closed position;

FIG. 2 is a front perspective view in an open position; and

FIG. 3 is a rear perspective view thereof in an open position.

The dash dot lines in FIGS. 2 and 3 represent fold lines.

We claim:

The ornamental design for a combined blotter pad and portfolio, as shown and described.
